UNITED STATES PATENT OFFICE.

AUGUST J. MOTTLAU, OF PITTSBURGH, PENNSYLVANIA, ASSIGNOR TO WESTINGHOUSE ELECTRIC & MANUFACTURING COMPANY, A CORPORATION OF PENNSYLVANIA.

THERMAL RELAY.

Application filed September 28, 1926. Serial No. 138,189.

My invention relates to circuit-protective devices and particularly to thermal relays.

An object of my invention is to provide a thermal relay that shall not be operatively affected by ambient temperature.

Another object of my invention is to provide a thermal relay that shall permit of such adjustment as to be operable over a relatively wide range of thermal conditions.

Another object of my invention is to provide a thermal relay that shall actuate the contact members associated therewith into and out of engagement with a snap motion.

In practicing my invention, I provide a pair of bimetallic members that are operatively secured together at corresponding ends thereof and a bridging member of substantially sinuous shape disposed between the other ends thereof and operatively secured thereto. A stationary contact member is mounted on one of the bimetallic members, and a movable contact member is mounted on the bridging member. The bimetallic members are so disposed that they are deflected in the same direction when subjected to the same temperature. Means are provided also for adjustably moving the ends, to which the operating member is secured, away from or towards each other in accordance with predetermined thermal conditions at which the bimetallic members shall be operable to actuate the bridging member laterally between the ends thereof. A heating coil is thermally associated with one of the bimetallic members for heating it in accordance with conditions in an electric translating device to be protected. The heating coil may be included in the circuit of the translating device.

In the drawings:

Fig. 1 is a front view of a device embodying my invention;

Fig. 2 is a top plan view thereof;

Fig. 3 is a view, in section, of the device illustrated in Fig. 1, taken on the lines III-III thereof;

Fig. 4 is a view of the device illustrated in Fig. 1 actuated to a position corresponding to a certain ambient temperature condition; and

Fig. 5 is a view of the device illustrated in Fig. 1 in an inoperative position.

In the drawings, a thermal relay 11 com-

prises a base member 12, a pair of bimetallic members 13 and 14 mounted thereon, and a bridging member 15, of sinuous shape, secured between the ends 16 and 17 of the bimetallic members by suitable means, such as rivets 18.

The bimetallic members 13 and 14 are of substantially L-shape having longer portions 19, and portions 20 of less length extending substantially at right angles to the portions 19, and upturned portions 21 which are secured together by a spacing member 22 and a pin member 23 the ends of which are hammered over the portions 21. The bimetallic member 14 is directly secured to the base 12 by means of a screw 14a, and the bimetallic member 13 is directly supported by the member 14 by means of the members 22 and 23.

A stationary contact mechanism 24 is secured to the elongated portion 19 of the bimetallic member 17 by a suitable screw member 25 that serves to clamp the bimetallic member securely against an apertured portion 26 of the mechanism 24. The member 24 is provided with an extended portion 27 at the end of which a pair of contact members 28 and 29 are insulatedly secured. The contact members 28 and 29 extend through the end of the portion 27 and are insulated therefrom by insulating washers 31 and secured thereto by nut members 32 that register with the screw threaded portions 33 and 34 of the terminal members 28 and 29. Conductors 35 may be connected to the terminal members 28 and 29 and to a control device for controlling an electric-energy translating device.

The bridging member 15 is provided with a contact member 36 which, in its operative position, as illustrated in Fig. 1, so bridges the contact members 28 and 29 that they are connected in series.

If it is desirable to increase or to decrease the longitudinal pressure on member 15, the ends 16 and 17 may be moved towards or away from each other by turning a screw-threaded adjusting member 37 in the proper direction. The screw-threaded adjusting means 37 registers with, and extends through, screw-threaded apertures (not shown) in the portions 21 of the bimetallic members 13 and 14.

The device embodying my invention, as illustrated in the drawings, is so arranged that the sides 38 and 39 of the bimetallic members 13 and 14 are the high-expansion sides thereof, and the sides 41 and 42 are the low-expansion sides. When both of the bimetallic members are subjected to an ambient temperature of a sufficiently high value, they will be deflected to a general position substantially as illustrated in Fig. 4 of the drawings. If one of the members, for instance, the member 13, is thermally energized to a higher temperature by a suitable heating coil 43 that is in circuit with a translating device, not shown, the member 13 will be deflected to such position that the member 15 will be caused to assume a position illustrated in Fig. 5 of the drawings when a predetermined current condition obtains in the translating device. When in this position, the contact member 36 is out of engagement with the contact members 28 and 29. Since the contact members 28 and 29 are in circuit with the control device, when in the position illustrated in Figs. 1, 3 and 4 of the drawings, it is evident that the control device will become deenergized when the contact member 36 is in the position illustrated in Fig. 5.

If it is desirable that the thermal relay 11 shall be operable when a relatively small current traverses the coil 43, the adjusting means 37 is turned in such direction that the ends 16 and 17 of the bimetallic members 13 and 14 are moved towards each other to thereby produce an initial longitudinal compression in the member 15. It is, therefore, evident that a relatively small expansion of the bimetallic member 13 is required to disengage the contact member 36 from the contact members 28 and 29.

If it is desirable that a large current shall traverse the coil 43 to actuate the thermal relay to the position illustrated in Fig. 5 of the drawings, it is only necessary to turn the adjusting means 37 in such direction that the ends 16 and 17 shall be moved away from each other. Therefore, a correspondingly large deflection of the member 13 will be necessary before the bridging member 16 is sufficiently compressed to actuate it to the position illustrated in Fig. 5 of the drawings.

My invention provides a relatively simple thermal relay that consists of a small number of parts and is easily manufactured. The device may be so adjusted as to be operable over a relatively wide range of conditions to be controlled and is so constructed that ambient temperature has substantially no effect upon its operation.

The invention comprises, in general, a pair of spaced-apart bimetallic members that are adapted to actuate a resilient bridging member into and out of engagement with a pair of relatively stationary contact members.

One of the bimetallic members is provided with a heating coil which is thermally energized in accordance with the current flowing in a circuit to be protected. Since one of the members is energized more than the other, the member receiving the greater amount of thermal energy will be deflected to thereby actuate the contact members on bridging member out of engagement with the stationary contact members.

Various modifications may be made in the device embodying my invention without departing from the spirit and the scope thereof. I desire, therefore, that only such limitations shall be placed thereon as are imposed by the prior art and the appended claims.

I claim as my invention:

1. The combination with a resilient bridging member of substantially sinuous shape, a contact member mounted thereon, a pair of bimetallic members for supporting said resilient member, said bimetallic members being so disposed in operative relation to each other as to deflect in substantially the same direction when subjected to the same ambient temperature variations, and a stationary contact member supported by one of said bimetallic members in operative relation to the other contact member, of means for thermally energizing one of the bimetallic members to cause it to actuate the bridging member to control the engaged and disengaged position of said contact members.

2. The combination with a pair of bimetallic supports disposed to maintain the distance therebetween substantially constant for all values of ambient temperatures, a resilient bridging member of substantially sinuous shape disposed between the supports in operative engagement therewith, and means for varying the initial distance between said supports, of means for thermally energizing one of said bimetallic supports more than the other to cause the bridging member to be deflected laterally between the supports.

3. The combination with a pair of bimetallic members of substantially L-shape, means for holding the short legs of said members relatively fixed, a resilient member of substantially sinuous shape disposed between the long legs thereof, and a contact member mounted in operative relation to the bridging member, of means for thermally energizing one of said bimetallic members to cause relative engagement of the contact member with the bridging member and disengagement therefrom.

4. A thermally-actuable circuit-controlling device comprising a pair of spaced apart co-extending substantially parallel bimetallic members disposed to be deflected in the same direction in response to ambient temperatures, means for adjustably securing corre-

sponding ends of said members in operative relation to each other, and a resilient bridging member having recurring substantially similar curved portions for operatively associating with a stationary contact member, of thermal means for energizing one of said bimetallic members more than the other to

cause said bridging member to be deflected with a snap motion.

In testimony whereof, I have hereunto subscribed my name this 13th day of September, 1926.

AUGUST J. MOTTLAU.
